DESIGN FOR A BASE CABINET CORNER FILLER

Jacques Stanitz, Warren, Ohio, assignor to Mullins Manufacturing Corporation, Salem,
Ohio, a corporation of New York

Application December 18, 1944, Serial No. 116,968

Term of patent 7 years

(Cl. D33—19)

To all whom it may concern:

Be it known that I, Jacques Stanitz, a citizen of the United States, residing at Warren, in the county of Trumbull and State of Ohio, have invented a new, original, and ornamental Design for a Base Cabinet Corner Filler, of which the following is a specification, reference being had to the accompanying drawing forming part thereof.

The single figure in the drawing is a perspective view of a base cabinet corner filler showing my new design. The dot-and-dash line showing is for illustrative purposes only.

I claim:

The ornamental design for a base cabinet corner filler, substantially as shown and described.

JACQUES STANITZ.
